DESIGN FOR A VANITY CASE

Ernest L. Warner, Los Angeles, Calif.

Application March 18, 1941, Serial No. 99,671

Term of patent 7 years

To all whom it may concern:

Be it known that I, Ernest L. Warner, a subject of the King of England and a resident of the city of Los Angeles, in the county of Los Angeles and State of California, have invented a new, original, and ornamental Design for a Vanity Case, of which the following is a specification, reference being had to the accompanying drawing, forming part thereof.

In the drawing:

I claim:

The ornamental design for a vanity case, substantially as shown.

ERNEST L. WARNER.
